G. Pierce,
Horse Rake.

No. 1040.

Reissued Mar. 22, 1884.

Fig. 2.

UNITED STATES PATENT OFFICE.

GIDEON PEIRCE, OF ERCILDOUN, PENNSYLVANIA.

IMPROVEMENT IN HORSE-RAKES.

Specification forming part of Letters Patent No. 26,293, dated November 29, 1859; Re-issue No. 1,640,
dated March 22, 1864.

To all whom it may concern:

Be it known that I, GIDEON PEIRCE, of Er-
cildoun, Chester county, Pennsylvania, have
invented a new and useful Improvement in
Horse-Rakes; and I hereby declare the follow-
ing to be a full and exact description of the
same, reference being had to the accompan-
ying drawings, making part of this specifica-
tion.

In the accompanying drawings, Figure 1 is
a plan of a horse-rake embodying my improve-
ment. Fig. 2 is a side view of the same with
one wheel removed.

a is an axle without teeth, revolving always
with one of the ground-wheels, while it is to
work loosely in the other, and carrying upon
it a cog-wheel, *b*.

c is a vertical rack adapted (in manner here-
inafter explained) to be thrown in or out of
gear with cog-wheel *b*. The said rack is at its
upper end pivoted to a frame, *d*, which frame
is pivoted at *e* to standards rising from the
main frame *h* of the implement.

f are the teeth, attached to the implement in
customary manner to admit of being raised at
the moment to discharge.

G is a guard or bar provided with mortises,
through which the teeth pass. The said bar
is attached to the frame *d* so as to be raised
or depressed therewith, and works at each end
on a small standard rising from the main frame
h to guide it in a proper path.

I is a lever provided with a friction-pulley,
i, and employed to press the rack *c* against the
cog-wheel *b*.

j is a second lever, which, when depressed,
exerts an upward pressure on the forward end
of the frame *d* in order to keep the teeth firmly
down to their work.

K are clearers, of customary construction.
In order to discharge the teeth, it is only
necessary to withdraw the foot from the lever
j and place it upon the lever *I*. This action,
bringing the rack *c* into gear with cog-wheel
b, causes the said rack to be drawn downward
by the motion of the machine, thereby elevat-
ing the teeth through the agency of the frame
d and bar *G*.

The levers *I* and *j* may be adapted to be op-
erated by either the foot or hand.

By this invention the driver is relieved from
the labor of elevating the teeth by hand. At
the same time the draft of the animal is equal-
ized.

I claim as new and of my invention herein
and desire to secure by Letters Patent—

The arrangement and combination of the
axle *a*, cog-wheel *b*, rack *c*, lever *I*, frame *d*,
bar *G*, standard *g*, and teeth *f*, operating sub-
stantially as and for the purpose set forth.

GIDEON PEIRCE.

Witnesses:

JAMES B. MODE,
LUKENS PEIRCE.
